UNITED STATES PATENT OFFICE

SAMUEL ZULLO, OF JERSEY CITY, NEW JERSEY

TELEPHONE-MESSAGE APPARATUS

Application filed September 3, 1927. Serial No. 218,142.

This invention relates to speech recording and transmitting devices of the type which automatically receives, records and transmits messages over the ordinary telephone during the absence of the subscriber.

The object of the invention is to provide a device of the character described comprising a standard speech transmitting instrument, such as a telephone, with a standard speech recording instrument, such as a dictaphone, together with such submechanisms as will provide an automatic apparatus adapted to receive an incoming telephone call, transmit a standard message advising the calling party that he is talking to an apparatus, receive and record a message and finally transmit such a message to the subscriber.

I have selected a standard dictaphone as the recording device because it is well known, may be considered as a standard in its field and because it may be used as dictaphone per se apart from its function as a part of my invention.

Accordingly my invention is embodied in an apparatus to accomplish the foregoing objects and as set forth in the following specification read in connection with the accompanying drawings in which

Fig. 1 is a plan view of an apparatus embodying my invention with parts removed and broken away.

Fig. 2 is a detail perspective view of certain parts shown in Figure 1.

Fig. 3 is an end view looking in the direction of arrow 3 in Figure 1 with parts omitted and broken away.

Fig. 4 is a rear view of the apparatus with parts omitted and broken away.

Fig. 5 is a detail sectional view on line 5—5 of Figure 1.

Inasmuch as a dictaphone is a well known instrument in use in thousands of places, only so much of it is shown and described as is necessary for an understanding of my invention. In describing the dictaphone itself the arrangement of the speaking tubes shown in the drawings must be disregarded because they are shown arranged in accordance with my invention.

Referring to the drawings the numeral 13

designates the dictaphone base or main casing which contains a motor 14, shown diagrammatically in Figure 3. The motor drives a pulley 15 on a record shaft 16 which is adapted to carry the usual cylinder record 55 17. The casing 13 carries two, upstanding brackets 18, 18 which support two shafts 19 and 20. 21 designates the usual dictaphone sound box slidably mounted on shaft 19 and clutched thereto by a clutching lever 23. 60 The latter is shown in its normal neutral position in the drawings, but when said lever is moved rearwards, to the left in Figure 3, the sound box is clutched to the operating shaft 19 and slides along said shaft as the 65 latter is rotated. The sound box is guided by a depending member 33 which slides on the shaft 20. The incoming speech, i. e. the dictated message is carried to the soundbox by a speaking tube and recorded on the recording cylinder 17, all in a well known manner.

The motor is usually connected to a lamp socket or other outlet by wires 24. The motor circuit is broken at contacts 25, but closed 75 by a switch 26 carried on a rod 27 pivoted at 28 to a hook lever 29 which is pivoted to the machine at 31. The hook lever 29 supports the dictaphone speaking tube which by its weight keeps the switch 26 away from 80 the contacts 25. When the operator lifts the tube to dictate, the rod 27 drops, the switch 26 closes the motor circuit and the dictaphone starts operating. This is all old in the art and thought to be adequate for an under- 85 standing of this invention.

For the purposes of my invention I provide the dictaphone with a second sound box 35 which is mounted and operates exactly like the sound box 21. The latter will be 90 called the transmitting sound box for purposes of identification, while box 35 will be called the receiving sound box. To the latter is affixed a speaking tube 22 ending in a mouth-piece 32 which rests by gravity in the 95 hook lever 29. The tube 22 and receiving sound box 35 functions in the same manner as the dictating or speaking tube on the standard dictaphone.

The transmitting sound box 21 is also pro- 100

vided with a speaking tube 36 with a mouth-piece 37 which is held in a predetermined fixed position in a bracket 38 secured to the dictaphone.

- 5 I use a standard telephone for starting and operating the apparatus. The telephone is shown in conventional form and comprises the stand 10, the transmitter 11 and the receiver 12. A shelf 40 is attached to the dictaphone base in any suitable manner and is adapted to support the telephone in a slightly inclined position as shown so that the transmitter 11 registers with the mouthpiece 37 and the telephone receiver registers with the mouthpiece 32.
- 10 While the inclined position of the telephone is not essential, it is preferred because in such position the receiver 12 hangs away from the stand 10 as best seen in Figure 4 and more space is obtained below the receiver for registry with the mouthpiece 32. For convenience in positioning the telephone, the shelf 40 is provided with an upstanding flange 41.
- 15 The operation and functioning of the apparatus is controlled by a timing mechanism which is automatically actuated by an incoming telephone call and which timing mechanism in turn automatically causes the dictaphone to operate a predetermined length of time so as to receive and record the incoming message. At the end of the period, the timing mechanism stops the operation of the dictaphone and returns certain parts to starting position ready for the next operation. The timing and control mechanism is preferably embodied in a unitary structure adapted to be mounted as an assembled unit on the base of the dictaphone.
- 20 To this end there is formed a bracket like casting 42 comprising a front wall 43 and a rear wall 44 joined by suitably placed transverse members 45, 45. Any suitable fastening means may be used for mounting this bracket on the dictaphone. The screw 46 in Figure 4 indicates such means. The bracket 42 supports a spring motor 47 adapted to be rewound by a suitable tool, not shown, applied to the rewinding shaft 48. The motor 47 drives a shaft 49 by means of gears 50 and 51. The shaft 49 carries outside the bracket a disk 52 having a notch 53 and a pin 54. The notch 53 is engaged by a pawl 55 which thus prevents the motor from rotating so long as the pawl engages the notch. In the bracket is further mounted a cam shaft 58 which carries a cam 59 adapted to cause the telephone receiver 12 to be lowered to cut off the telephone circuit (hang up the receiver) at the end of operations. The cam has a neutral surface or seat 60 upon which rests the rear end of the hook lever 29 which is being kept on said seat by a spring 61. The cam also has a lifting portion 62 and a stop 63. The 65 cam shaft 58 is provided with a pin 64 within

the bracket 42 and an arm 65 outside the bracket, see Figure 1. The inside pin 64 is connected by a chain 66 with the armature 70 of an electromagnet 67. The outside arm 65 rests on the upper end 68 of a pivoted lever 69 adapted to be operated by the aforesaid pin 54 in the disk 52. The electromagnet 67, shown as a two coil magnet or relay, is conveniently mounted on a shelf 71 which may be a part of the bracket 42.

70 The pawl 55 is carried by a stop shaft 72. Inside the bracket 42 this shaft 72 carries a stop arm 73 and a starting arm 74, see Figure 2. The stop arm 73 engages a stop pin 75 on the governor shaft 76 which carries a governor 77, Figure 1. The starting arm 74 rests on the bevelled head 78 of a slide 79 mounted in a block 80 affixed to the bracket wall 43.

75 The pawl 55 and the starting arm 74, both in the stop shaft 72, rest by gravity on the disk 55 and head 78, respectively, and thus tend to keep the stop arm 73 normally in the path of movement of the pin 75 on the governor shaft.

80 The governor shaft 76 is rotated by a train of gears 78, 79 and 80. The gear 78 is mounted on the shaft 49. On the latter and in front of the wall 43 of the bracket 42, see Figures 1 and 5, there is mounted a cam 82 which 85 operates a vertical slide 83 which at its top carries a turntable head 84. The latter carries a pin 85 and a finger 86. The shaft 49 further carries a returning cam 87 adapted to engage a knob 88 on the depending guide 90 piece 33 from the recording unit 21. The pin 85 engages a slotted lever 90 secured to the clutching lever 23 on the recording unit 21.

90 The relay 67 is energized by means of a small local circuit shown in Figure 4. The 105 relay 67 is connected in series with a battery 92 and a relay 93 which is adapted to be energized from the telephone bell circuit 94. When the bell 195 rings, the relay 93 is energized and closes the circuit through the battery and the relay 67 energizing the latter.

95 The use of the apparatus presupposes that a suitable "informing" message has been spoken into the mouthpiece 37 and conveyed through the tube 36 to the unit 21 and recorded on the record cylinder 17, this operation being done in exactly the same manner as when dictating to the dictaphone. During this operation, however, the operator manipulates the finger piece 86 to turn the pin 85 out 110 of the groove in the slotted member 90. In other words, the timing mechanism is disconnected from the dictaphone, the informing message recorded by the latter and the parts restored to normal position as shown. On a 115 small part of the cylinder 17 there is now an informing message ready to be transmitted to the party who calls up during the absence of the subscriber.

120 Thereafter the dictaphone mechanism is 130

placed in position ready to operate. That is, the lever 23 of the recording unit 21 is put in clutched position with the pin 85 engaging the slotted lever 90, see Figure 2. At the 5 same time, the corresponding clutching lever 123 of the dictaphone receiving unit 35 is put in clutching position.

When a party desires to receive telephone calls during his absence, he places the telephone on the shelf 40 so that the transmitter and receiver register with the mouthpieces 37 and 32 respectively. When a call comes in, the relay 67 is energized as aforesaid and the armature 70 pulls down the pin 64 through the chain 66, thereby rocking the shaft 58 anticlockwise and rotating the cam 59 a short distance. The spring 61 therefore pulls down the rear end of the hook lever 29 and raises the front end which carries the mouthpiece 32 and the telephone receiver 12. Consequently the latter is lifted off the telephone hook and the line is ready for messages. The rear end of the hook lever 29 now rests on the low part of the cam 59 against the stop 63. The anticlockwise movement of the shaft 58 has also lowered the pin 65 to tip the lever 69 so that its lower end projects into the path of the pin 54 on the disk 52.

The lowering of the hook lever 29 on the 10 cam 59 closes the motor circuit, see Figure 3; the motor commences to operate and the two units 21 and 35 commence to move on shaft 19. Immediately thereafter, because there is nothing to prevent it, the informing message 15 notifying the caller to deliver his message to the machine, is spoken into the telephone transmitter 11 from the sound box 21 and the tube 36. At this time the two sound boxes 21 and 35 have moved along the record cylinder a certain distance depending upon the length of the informing message and the caller has been notified of the absence of the subscriber.

It will be noticed, then, that when the 20 sound box 21 moves, the slotted lever 90 will strike the sliding member 79 projecting from the block 80 and consequently the head 78 will move to the left in Figure 2 and will lift the starting arm 74 and rock the shaft 72 anticlockwise, thereby lifting the stop arm 73 away from the governor stop pin 75, and the pawl 55 out of the notch 53 on disk 52. The spring motor 47 is now free to rotate.

The rotation of the motor operates the governor to steady the movements of the parts as is obvious and also rotates the shaft 49. The latter, through the instrumentality of the cam 82 causes the slide 83 and pin 85 to rise, thus moving the clutching lever 23 back to 25 normal or neutral.

At the same time, however, the returning cam 87 has rotated to engage the pin 88 to return the unit 21 to starting position. This takes place during one revolution of the 30 shaft 49. When it has completed its revolu-

tion, the pawl 55 drops into the notch 53 and prevents further rotation. But at this time, the pin 54 has engaged lever 69 to lift the arm 65 to rock the shaft 58 and cam 59 clockwise. Consequently the hook lever 29 is lifted and the mouthpiece and telephone receiver is lowered to cut off the telephone connection.

To recapitulate:—When the telephone rings the relay 67 is energized and through the chain 66 rocks the shaft 58 a short distance anticlockwise. This causes operation of the cam 59 to lower the lever 29 to lift the receiver off the hook and close the motor circuit. The dictaphone commences to work and moves both sound boxes 21 and 35 to the left in Figure 4. The sound box 21 immediately transmits the short informing message on the cylinder 17 into the telephone transmitter 37 advising the calling party. Simultaneously therewith the slotted lever 90 of the unit 21 has moved slide head 78 to lift arm 74 to rock the shaft 72 anticlockwise, thereby freeing the governor mechanism from the stop arm 73, and freeing the disk 52 from the pawl 55. Consequently the spring motor is free to rotate. It rotates shaft 49 and the cams 82 and 87 do two things in combination. First, cam 82 raises the pin 85 and unclutches 21 from the shaft 19. Second, the returning cam 87 strikes the knob or pin 88 on unit 21 (which has moved up to the cam) and returns the unit 21 to normal neutral position.

We have now reached a point in the operation where the telephone call has been received and the apparatus automatically started. The informing message has been transmitted from the dictaphone to the telephone transmitter via tube 36 and the sound box 21 has been unclutched from the shaft 19 and moved back into starting position. It will, however, be remembered, that during these operations, the dictaphone motor is continuing to run the dictaphone. Consequently as soon as the informing (outgoing) message has been spoken, the caller may respond with an incoming message which will be delivered by the telephone receiver to the second sound box via the tube 22, and from the second box 35 the incoming message will be recorded on the record cylinder 17, because these two elements keep on operating while the first sound box is being moved back to starting position.

The apparatus stops when the stop shaft has made one complete revolution and the pin 54 has gone around once and now strikes the lever 69, raising its upper end to lift the arm 65 and rotate the shaft 58 clockwise, causing the cam 59 to raise the hook lever 29 back to normal position, break the motor circuit and the cycle of operations is completed.

The cycle of operations may therefore be summarized as follows:—The ringing of the telephone bell energizes the relay 67, which pulls down pin 64 to rock the shaft 58 to move cam 59 anticlockwise away from under the

hook lever 29. The latter is pulled down by the spring 61 to lift the telephone receiver off the hook and close the motor circuit. This starts the dictaphone and both sound boxes 21 and 35 commence to travel along the recording cylinder 17.

The movement of sound box 21 operates to disengage the pawl 53 from the disk 52 through the instrumentality of the elements 10 shown in Figure 2 and starts the timing mechanism.

During the first movement of the sound boxes, the informing message is sent out through sound box 21 and at the same time 15 at the end of the informing message, the slide 83 has risen to move lever 23 to unclutch the first sound box and the returning cam is ready to return said sound box to starting position.

As soon as the informing message has been 20 spoken, the incoming call is received by the second sound box and recorded, while the first sound box returns to initial position. When this has been accomplished, the motor circuit is automatically broken because the cam 59 is 25 operated clockwise back to starting position to lower the hook lever, and the spring motor is stopped because the pawl 55 falls into the notch 53 of the disk 52.

At the end of the operation we therefore 30 find sound box 21 back into starting position, but sound box 35 has advanced along the shaft 19 and recorded the incoming call on the cylinder 17 and stops in its new position.

If the incoming message has not been completed, the caller rings again. The same 35 operations are gone through with and at the end thereof sound box 21 is again back into starting position, but sound box 35 has been still further advanced along the shaft 19.

40 Therefore, at the beginning of each call the two sound boxes travel together a distance determined by the length of the informing message. Thereafter the first sound box returns to starting position, while the second 45 sound box continues its travel and records the incoming message.

In the instance illustrated it will be seen therefore, that the apparatus is of sufficient capacity to permit a complete informing— 50 outgoing—message, and can record an incoming message of a length dependent upon the length of time it takes to return the first sound box to starting position.

To illustrate:—Assume that the first sound 55 box 21 travels one quarter of an inch in order to transmit an informing message to the effect that the subscriber is out but will return at a certain time and for the caller to deliver his message to the apparatus. When this has 60 been accomplished, both sound boxes have travelled one quarter of an inch. The second sound box, however, has not recorded anything, but will commence to do so, as soon as the incoming message is being delivered.

65 The first sound box is now unclutched from

the dictaphone and returns at a speed, not depending upon the dictaphone operations but dependent upon the rate of speed at which the spring motor operates and the contour or side of the returning cam 49, because the sound box 21 does not return to starting position until the said cam strikes the knob 88 and moves it back. During this time, of course, the second sound box records the incoming call and may for this purpose have a travel of perhaps up to half an inch.

At the beginning of the second operation, the two sound boxes again travel together, and for a space of another one quarter of an inch the second sound will again travel idly, thereby automatically separating the incoming calls.

In practise, the length of travel for the purpose of transmitting the outgoing informing message will be made as short as is practical, 85 while the return stroke of the sound box 21 will be delayed as long as is practical in order to permit the sound box 35 to receive the incoming call while travelling at dictaphone speed. This is accomplished by the proper 90 proportioning of the timing mechanism elements.

As a matter of convenience there is placed a bar 95 across the dictaphone, and said bar is spaced and numbered as shown to indicate 95 the number of incoming calls which may be received. The sound box 35 carries a pointer 96. It is obvious, therefore, that the position of the pointer indicates to the returning subscriber the number of calls received during 100 his absence.

The telephone may now be removed and the dictaphone started to relay or retransmit to the subscriber through sound box 35 and tube 22 the recorded calls made during his 105 absence.

When it is desired to use the dictaphone for ordinary dictating purposes, the timing mechanism is rendered inoperative by the operator taking hold of the finger piece 86, Figure 2, and turning the pin 85 out of engagement with the slotted lever 90 and placing the latter in neutral position. Therefore, when the dictaphone starts operating, the telephone being of course removed, the first 110 sound box 21 will not travel along the shaft 19. The operator, however, starts the dictaphone in the usual manner by a manually operated switch, not shown, and dictates through mouthpiece 32 and tube 22 to the 120 second sound box which operates as usual. The only difference is that when the apparatus is operated as a dictaphone per se, the available recording space is diminished for a 125 distance from the inner end of the record to the point where the second sound box begins to record.

From the foregoing it will be seen that without making any material change in the dictaphone except adding the second sound 130

box, which is a standard dictaphone part, it is made available for the purposes of the invention. The timing mechanism is simple and sure in operation and is the medium through which the dictaphone and the telephone are combined to accomplish the result aimed at.

In practise the timing mechanism may be concealed by a suitable casing, not shown. Other details may be changed, but this is believed to be within the scope of the person skilled in the art and within the legitimate and intended scope of the appended claims.

I claim:—

1. In combination, a telephone set, a speech recording instrument of the character described having a recording cylinder and two sound boxes in sound transmitting relation to the cylinder which latter bears a recorded message, means for placing the transmitter and the receiver of the telephone set in operative relation to the two sound boxes and means for operating the latter so that at each operation one sound box transmits the said same recorded message to the telephone transmitter and the other sound box records an incoming message on the cylinder from the telephone receiver.

2. In combination, a telephone set, a speech recording instrument of the character described having a single recording cylinder and two sound boxes, said cylinder having a message recorded thereon, means for operating the said two sound boxes and controlling mechanism regulating the operation of the sound boxes whereby one of them transmits the recorded message to the telephone transmitter while the other sound box is inactive and whereby the other sound box records an incoming message on said cylinder from the telephone receiver while the first sound box returns to initial position.

3. In combination, a telephone set, a speech recording instrument of the character described having a recording cylinder and two sound boxes, a telephone set, means for placing the telephone transmitter and the telephone receiver in operative relations with said sound boxes, means actuated by the signalling current of the telephone circuit to cause the said recording instrument to operate, a controlling mechanism actuated by one of said sound boxes for controlling the period of operation of the other sound box and for returning the said first sound box to starting position each time the said recording instrument is operated.

4. In combination, a telephone set, a speech recording instrument of the character described having a recording cylinder and two sound boxes, mechanism for causing said recording instrument to operate both of said sound boxes from given starting positions to given finishing positions to transmit and record, respectively from and to said recording

cylinder, an outgoing and an incoming message via the telephone transmitter and telephone receiver, respectively, and means in said mechanism to return the transmitting sound box to its starting position while the receiving sound box moves to its finishing position.

5. In combination, a telephone set, a speech recording instrument of the character described having a recording cylinder and two sound boxes, mechanism for causing said recording instrument to operate both of said sound boxes from given starting positions to given finishing positions with respect to the recording cylinder to transmit and record thereon, respectively, an outgoing and an incoming message via the telephone transmitter and telephone receiver, respectively, and means in said mechanism to return the transmitting sound box to its starting position while the receiving sound box moves to its finishing position, and visible means operated by the receiving sound box for indicating the number of operations of the said recording instrument.
